ATTORNEY

UNITED STATES PATENT OFFICE.

JOSEPH H. MONTGOMERY, OF SAN JOSE, CALIFORNIA.

FORCED-FEED OILER.

Application filed August 23, 1921. Serial No. 494,597.

To all whom it may concern:

Be it known that I, JOSEPH H. MONTGOMERY, a citizen of the United States, and resident of San Jose, in the county of Santa Clara and State of California, have invented 5 certain new and useful Improvements in Forced-Feed Oilers, of which the following is a specification.

My invention relates to those devices 10 known as forced feed oilers.

One object of the said invention is to provide an oiler of the character indicated with which to automatically and continuously supply oil to the valve stem and push rod 15 ends of the rocker arms of internal combustion engines. Further objects are to provide a device of the character indicated that will be simple in form and construction, easily adaptable to all forms of engines, that 20 has no working parts to wear loose or get out of order and that will be highly efficient in its practical application.

In the drawings,—

Figure 1 is a plan view of my invention as 25 adaptable for six cylinder internal combustion engines.

Figure 2 is a side elevation of the same.

Figure 3 is a cross-section on line 3—3 of 30 Figure 2.

Figure 4 is an end view, partly in section, showing the device in operative position on an engine.

Referring more particularly to the drawings, at 1 I show an oil carrying tube formed 35 with curved ends and the sides equidistant and parallel with relation to the longitudinal axis thereof, the ends of the said tube being spaced a distance from each other and having connecting ells 2 and 3 secured 40 thereto as shown. Connecting with said tube 1 through the medium of ells 2 and 3 are inlet and outlet pipes 4 and 5 respectively.

Mounted upon and depending from oil 45 carrying tube 1 and connecting therewith are a number of smaller, short tubes 6 spaced from each other and in the relative positions shown. The number of these tubes 6 varies with the type of engine and number of cylinders of the same.

Secured to said tube 1 and along the longitudinal axes of tubes 6 are wires 7, the same being the supports for the wicks 8 which fill the interior of tubes 6 and extend a distance below the same. The wicks 8 are held 55 in operative relation to the parts to be oiled by means of strips 9 mounted upon tube 1, the same having openings 10 therein through which bolts 11, of the engine pass.

In operation the oil is drawn from the 60 crank-case 12 by means of oil pump 13 and is forced through inlet pipe 4 into oil tube 1 and thence back into the crank-case through outlet pipe 5. Thus the oil has a 65 steady and continuous circulation, under a slight pressure through the tube 1 where it comes into contact with wicks 8 at points 14. Said wicks 8, by means of their fibrous nature, draw the oil from tube 1 and when 70 they become saturated the oil drips upon the parts to be lubricated, automatically and in uniform quantity.

In the present types of overhead valve 75 constructed engines no provision is made for oiling the valve stem and push rod ends of the rocker arm, therefore the same is done with an oil can thus the oiling of the same is dependent entirely upon manual labor, and consequently the said parts suffer from 80 lack of sufficient lubricant.

It is apparent however that with my invention in place these parts receive oil all the time they are operating and in sufficient quantities to freely and efficiently oil the same. The device is simple to construct as 85 there are no working parts except the lubricating pump which is a part of every automobile engine and consequently nothing to be adjusted nor to wear out. The same is easily installed. Simply remove the rocker 90 arm cover 15 and place the device in position on bolt 11, replace the cover and tighten up on the nut 16, which holds both the oiler and the cover securely in place.

It is to be understood, of course, that 95 while I have herein shown and described one particular embodiment of my invention that changes in form and construction may be made within the scope of the appended claim.

I claim:

An oiler comprising an oil carrying tube having sides arranged parallel with the longitudinal axis thereof; the said tube having spaced inlet and discharge openings therein and a number of shorter tubes depending therefrom and connecting therewith and spaced in pairs a distance from the trans-

verse axis of said oiler; and each pair spaced an equal distance from each other 10 pair along the longitudinal axis of said first mentioned tube; drip wicks mounted in and depending a distance below said second mentioned tubes, and means for mounting the oiler upon a fixed support.

JOSEPH H. MONTGOMERY.
